Primary Examiner — David G Muller*Assistant Examiner* — Nathan M Johnston(74) *Attorney, Agent, or Firm* — Sughrue Mion, PLLC(57) **CLAIM**

The ornamental design for a table, as shown and described.

DESCRIPTION

FIG. 1 is a perspective view of a table.

FIG. 2 is a front elevation view thereof. A rear elevation view is a mirror image of the front elevation view.

FIG. 3 is a left side elevation view thereof.

FIG. 4 is a top plan view thereof.

FIG. 5 is a bottom plan view thereof.

FIG. 6 is an enlarged cross-sectional view taken along the line 6-6 in FIG. 4; and,

FIG. 7 is an enlarged cross-sectional view taken along the line 7-7 in FIG. 4.

The broken lines shown in the drawings illustrate portions of the table that form no part of the claimed design.

1 Claim, 7 Drawing Sheets(56)
